DRAFTING MACHINE

Charles Hubbard Little, Cleveland, Ohio, assignor
to Universal Drafting Machine Corporation,
Cleveland, Ohio, a corporation of Ohio

Application February 25, 1946, Serial No. 649,861

10 Claims. (Cl. 33—79)

1

The present invention relates to parallel motion mechanisms or arms provided with counterpoise means and, more specifically to a drafting machine comprising a parallel motion arm of the wheel and band type comprising counterpoise mechanism for part or all of the arm.

One of the principal objects of the invention is the provision of a novel and improved drafting machine of the wheel and band type, having the bands and wheels completely enclosed, which machine will be simple in construction, inexpensive to manufacture, accurate in operation, will not be bulky and ungainly in appearance, and which can be readily provided with means for counterbalancing the weight of any part of the arm, as desired.

Another of the principal objects of the invention is the provision of a novel and improved drafting machine of the wheel and band type comprising improved means for counterbalancing the weight of the arm when the machine is used on an inclined drawing surface.

The invention resides in certain constructions and combinations and arrangements of parts and further objects and advantages will be apparent to those skilled in the art to which the invention relates from the following description of the preferred embodiment described with reference to the accompanying drawings forming a part of this specification in which similar reference characters designate corresponding parts and in which

Fig. 1 is a plan view of a drafting machine embodying the present invention, attached to a drawing board;

Fig. 2 is an enlarged plan view of the anchor portion of the drafting machine shown in Fig. 1;

Fig. 3 is a view similar to Fig. 2 but showing the parts in a different operative position;

Fig. 4 is a sectional view, with portions in elevation, approximately on the line 4—4 of Fig. 2; and

Fig. 5 is a sectional view, with portions in elevation, approximately on the line 5—5 of Fig. 1.

The drafting machine shown in the drawings comprises a two-section, parallel motion mechanism or arm of the wheel and band type having one end detachably connected to a drawing board and the other or free end provided with rulers or other instruments which it is desired to move about the drawing board or the like. The parallel motion mechanism or arm comprises two angularly movable sections each comprising a pair of wheels of equal diameter encircled by a flexible band. The upper or anchor

2

section comprises wheels 10, 11 encircled by an endless band 12 and held in spaced relation by an expandable strut A operatively connected thereto for relative rotation with respect to the strut in a manner hereinafter described.

The upper wheel 10 is formed integral with a member 14 pivotally connected, as by pivots 15, 16 the latter of which is adjustable, to a bracket member 17 forming a part of the anchor assembly, which bracket member is adapted to engage over the upper edge of the drawing board B and be detachably fixed thereto by a clamp screw 18 located underneath the drawing board and having threaded engagement in a suitably tapped aperture in the lower end of projecting arm 20 formed integral with the anchor bracket. The upper end of the clamp screw 18 is provided with a board-engaging member 21 connected thereto by loose joints which permit the members to set properly against the underside of the board. The front side of the member 14 is provided with an adjustable stop 22 threaded onto the lower end of a pin 23 fixed in the member 14, which stop is adapted to engage a flange or plate-like projection 24 on the bracket 17 immediately above the drawing board B.

The strut A comprises yoke or yoke members 25, 26 located at the anchor and elbow ends, respectively, of the anchor section of the arm and connected together and held in spaced relation by tubular side portions or members 27, 28. The anchor yoke 25 is rotatably connected by anti-friction bearings 30, 31 to a headed bolt or pivot member 32 fixedly secured in a boss 33 on a web 34 within the member 14 by jam nuts 35, 36. The bolt 32 forms a pivot for the strut A. The yoke member 25 is provided with a downwardly extending boss 37 on its lower side having a central aperture 38 therethrough so formed as to provide an inwardly projecting annular flange 40 at the lower end of the boss. The head 41 of the bolt 32 engages the inner race of the upper bearing 30 and clamps both inner races therebetween and the upper surface of the boss 33. The outer races of the bearings 30 and 31 are fixedly secured within the aperture 38 located in the yoke 25 by a threaded ring 42 having threaded engagement with a threaded intermediate part of the aperture. The upper end of the aperture 38 is normally closed by a removable cover 43. The construction is such that the anchor strut A is supported by the bearings 30, 31 for rotation about the center of the wheel 10 as an axis.

The yoke 26 of the anchor strut A located at the elbow of the arm is pivotally connected to

the wheel 11 for rotation about the center of the wheel as an axis by a bolt 45 similar to the bolt 32, previously referred to. The wheel 11 is formed integral and concentric with the wheel 46 of the strut C of the protractor section of the arm and the two wheels are fixed to the pin 45. The two yoke members 26, 47, the latter being the yoke member of the protractor strut C at the elbow of the arm, are pivotally connected with respect to each other and the wheel assembly 10 comprising the wheels 11, 46 and the bolt 45 by anti-friction bearings 50, 51, respectively, in a manner similar to that in which the yoke 25 is rotatably connected to the wheel 10. The bearings 50, 51 are located in apertures 52, 53 in the yoke members 26, 47, respectively, similar to the aperture 38 in the yoke member 25. The apertures 52, 53 are provided with removable covers 54, 55 respectively, similar to the cover 43 for the aperture 38.

The protractor section of the parallel motion arm, that is, the section comprising the protractor head and rulers, etc., is similar in construction to the anchor section already described and comprises in addition to the wheel 46, previously mentioned, a wheel 56 of equal diameter and held in spaced relation with respect to the wheel 46 by the strut C similar in construction to the strut A. The wheels 46, 56 are encircled by an endless band 57 similar to the band 12. In the embodiment shown, the wheel 56 located at the free end of the parallel motion arm forms a part of the instrument head, designated generally as D, or, conversely, the instrument head is a part of the parallel motion arm. Alternatively, the instrument head could be constructed as a separate unit and detachably secured to the wheel 56.

The struts A, C are expandible or adjustable in length and separable intermediate their ends to facilitate assembly and replacement of the bands 12, 57 and for the purpose of tensioning the same, etc. The tubular side members of the struts and the flexible bands are preferably similar in construction to those disclosed in a copending application of Charles H. Little et al., Serial No. 631,334, filed November 28, 1945, entitled Drafting Machine and are not herein shown and described in detail. Suffice it to say that the tubular side portions proper of the struts are discontinuous intermediate their ends and have their adjacent ends connected together by tubular-like nut members 58 rotatable in one direction to expand the strut and tense the band and in the opposite direction to release the tension on the band and loosen the nut so that it can be moved longitudinally of the strut to expose a portion of the band. The bands shown are separable to facilitate assembly and replacement thereof and the connecting means employed is relatively thin or small so that the bands can be threaded about the wheels while they are assembled with the struts.

The instrument head D is not herein shown and described in detail and may be of any desired construction. Preferably it is similar to that disclosed and claimed in my copending application Serial No. 745,800, filed May 3, 1947, entitled Drafting Machine, to which reference is made for a complete disclosure thereof. For the present purpose, it is sufficient to say that the instrument head comprises a ruler assembly including a hand grasp 60, a member 61 forming one element of a protractor proper, one or more rulers 62, 63 detachably secured to a ruler

or chuck arm 64, and means for selectively clamping the assembly to the wheel member 56 including a clamp 65 and indexing mechanism operated by a thumb piece 66. The instrument head also comprises a normally stationary protractor element 67 which cooperates with the rotatable element to indicate the angular position of the rulers with respect to a base line.

The present invention contemplates the provision of individual counterpoise means for each section of the parallel motion arm, which counterpoise means is simple in construction, inexpensive to manufacture, will not be bulky and ungainly in appearance, and which can or cannot be readily incorporated in the drafting machine, as desired. Each of the counterpoise mechanisms comprises a counterpoise force producing means operatively connected to the strut of the section of the arm which it is to balance and to the supporting wheel of the section, that is, the wheel closest to the anchor end of the arm. Both of the counterpoise mechanisms shown, that is, the counterpoise mechanism for the anchor section and the counterpoise mechanism for the protractor section of the parallel motion arm are alike in principle of operation and construction and only the counterpoise mechanism for the anchor section of the arm is shown and described herein in detail. Those parts of the counterpoise mechanism for the protractor section of the arm which are shown in the drawings are designated by the reference character used to designate the corresponding part in the mechanism for the anchor section with a prime mark affixed thereto.

The head 41 of the bolt 32 is provided with an eccentric pin 70 projecting from the top more or less in the nature of a crank pin, the cross-section of which pin is preferably elliptical in shape or approximately so with its major axis generally parallel to the upper edge of the drawing board or generally normal to a vertical plane through the axis of rotation of the strut when attached to an inclined drawing board or table. The pin 70 constitutes a cam at or adjacent to one end of the pivot 32, which cam is engaged by one end of a composite plunger or cam follower E slidably supported for linear movement by a tubular bushing 71 in an aperture 72 in the yoke 25. The aperture 72 is located in the longitudinal centerline of the strut and the centerline of the aperture intersects the axis of rotation of the strut. The plunger E is continuously urged in a direction to engage the pin 70 by a compression spring 73 located within an adjustable tubular assembly F detachably connected to the yoke 25.

The composite plunger or cam follower E interposed between the crank pin or cam 70 and the counterpoise spring 73 comprises a body member 74 slidably supported within the bushing 71 and a headed member 75 provided with a tapered shank by virtue of which it is fixedly retained in the left-hand end of the member 74, see Fig. 4. The head of the member 75 is provided with a cam-engaging flat surface 76 of considerable length which engages the side of the crank pin or cam 70. The opposite or right-hand end of the member 74 has a headed pin-like member 77 rotatably secured therein through the medium of a reduced shank portion rotatably supported in a suitable aperture in the end of the member 74. The head of the member 77 engages one end of the counterpoise spring 73. The

opposite end of the spring abuts the closed end of a tubular member 78 of the assembly F.

The tubular assembly F comprises two telescoped tubes 78 and 80 having threaded engagement with each other so that the effective length of the assembly can be varied by rotating the outer tube 78 relative to the inner tube 80. The left-hand end of the inner tube 80 is reduced and provided with threads adapted to cooperate with internal threads in the enlarged right-hand end of the aperture 72. The construction is such that when the drafting machine is intended to be used on a horizontal board, the counterpoise means can be readily removed by merely unscrewing the tubular assembly F from the yoke 25, withdrawing the member 14 through the right-hand end of the aperture 72, and removing the headed member 75 through the opening normally closed by the cover 43. The parts are so proportioned that this can be readily accomplished. If desired, the machine can be manufactured, omitting the counterpoise mechanism, which counterpoise mechanism may be supplied at any future time. In the event the counterpoise mechanism is not desired, a pin similar to the pin 32 but omitting the crank pin may be substituted for the pin 32. The exposed end of the aperture 72 may be closed by a suitable plug.

The direction of the counterpoising force produced by the counterpoise force producing spring 73 will be parallel to the direction of linear movement of the plunger or cam follower E and normal to the point of contact of the member 75 with the pin 76 and will be applied to the supporting member or wheel at an increasingly greater distance from the center of rotation of the strut as the strut is rotated in either direction from its normal vertical position shown in Fig. 2. The fact that the counterpoising force produced is always parallel or generally parallel to the direction of movement of the cam follower, simplifies the construction and increases the accuracy of the counterbalance. The maximum distance from center is obtained when the anchor section of the arm is substantially parallel with the upper edge of the drawing board, assuming that the upper edge of the drawing board is in a horizontal plane when the board is in a vertical position. The positions assumed by the various parts when the anchor section is rotated about 45° to the left of the vertical or normal position are shown in Fig. 3.

As previously stated, the cross-sectional shape of the crank pin or cam 70 is substantially elliptical so as to compensate for such things as change in spring pressure incident to a change in spring length, etc. It will be readily apparent that by changing the shape of the crank pin or cam 70 and by changing the force of the compression spring 73, a perfect balance can be obtained under all conditions of operation for various board angles.

From the foregoing it will be apparent that the objects of the invention heretofore enumerated and others have been accomplished and that there has been provided a novel and improved drafting machine having counterpoise mechanism which can or cannot be employed, as desired. The present invention is particularly advantageous for the manufacturer because it avoids the necessity of making distinctly different machines for use on horizontal and vertical boards. The present machine can be supplied with or without the counterpoise mechanism without materially affecting the appearance of the machine.

A machine originally supplied without the counterpoise mechanism can be readily converted for use with inclined boards by merely adding the counterpoise mechanism, which is an extremely simple matter especially if the original machine included a bolt similar to the bolt 32.

While the preferred embodiment of the invention has been described in considerable detail, I do not wish to be limited to the particular construction shown which may be varied within the scope of this invention and it is my intention to hereby cover all adaptations, modifications and uses thereof which come within the practice of those skilled in the art to which the invention relates and within the scope of the appended claims.

Having thus described my invention, I claim:

1. In a drafting machine or like device, a pair of wheels, a strut pivotally connected with respect to said wheels for rotation about axes concentric therewith, a flexible band encircling said wheels, means for supporting one of said wheels, a cam eccentrically fixed with respect to said supported wheel, said cam being generally elliptical in shape and having its minor axis substantially in the plane of the centers of the cam and said supported wheel, a cam follower slidably supported in said strut and adapted to engage said cam, and counterpoise spring means carried by said strut continuously urging said cam follower into engagement with said cam.

2. In a drafting machine or like device, a pair of wheels, a strut pivotally connected with respect to said wheels for rotation about axes concentric therewith, a flexible band encircling said wheels, means for supporting one of said wheels, a pin eccentrically fixed with respect to said supported wheel, said pin being generally elliptical in shape and positioned with its major axis generally normal to a vertical plane through the axis of relative rotation between the supported wheel and strut when the drafting machine is attached to an inclined drawing board or table, a member slidably supported in said strut and adapted to engage said pin, and counterpoise spring means carried by said strut continuously urging said member into engagement with said pin.

3. In a drafting machine or like device, a pair of wheels, a strut pivotally connected with respect to said wheels for rotation about axes concentric therewith, a flexible band encircling said wheels, means for supporting one of said wheels, a cam eccentrically fixed with respect to said supported wheel, said cam being generally elliptical in shape and having its minor axis substantially in the plane of the centers of the cam and said supported wheel, a cam follower having an elongated transversely extending surface adjacent to one end adapted to engage said cam, means for slidably supporting said cam follower in said strut for linear movement toward and from said cam, and counterpoise spring means carried by said strut continuously urging said cam follower into engagement with said cam.

4. In a drafting machine or like device, a pair of wheels, a strut pivotally connected with respect to said wheels for rotation about axes concentric therewith, a flexible band encircling said wheels, means for supporting one of said wheels, a cam eccentrically fixed with respect to said supported wheel, said cam being generally elliptical in shape and having its minor axis substantially in the plane of the centers of the cam and said supported wheel, a cam follower slidably supported in said strut, a tubular member detach-

ably connected to said strut, and counterpoise spring means within said tubular member continuously urging said member into engagement with said pin.

5. In a drafting machine or like device, a pair of wheels, a strut pivotally connected with respect to said wheels for rotation about axes concentric therewith, a flexible band encircling said wheels, means for supporting one of said wheels, a cam eccentrically fixed with respect to said supported wheel, said cam being generally elliptical in shape and having its minor axis substantially in the plane of the centers of the cam and said supported wheel, a cam follower having an elongated transversely extending surface adjacent to one end adapted to engage said cam, means for slidably supporting said cam follower in said strut for linear movement toward and from said cam, a tubular assembly detachably connected to said strut, counterpoise spring means within said tubular assembly continuously urging said member into engagement with said pin, and means for adjusting the force of said counterpoise spring.

6. In a drafting machine or like device, two members pivoted with respect to each other, a cam fixed with respect to one of said members and eccentric to the pivotal axes therebetween, a cam follower movably supported by the other of said members and adapted to engage said cam, said cam being generally elliptical in shape and having its minor axis substantially in the plane of the centers of the cam and the pivot, and counterpoise spring means continuously urging said cam follower into engagement with said cam.

7. In a drafting machine or like device, a wheel member, a strut member pivotally supported with respect to said wheel member for rotation about an axis concentric with said wheel member, a flexible band encircling said wheel member, a cam fixed with respect to one of said members and eccentric to said axis, a cam follower movably supported by the other of said members and adapted to engage said cam, said cam being generally elliptical in shape and having its minor axis substantially in the plane of the centers of the cam and the wheel member, and counterpoise spring means continuously urging said cam follower into engagement with said cam.

8. In a drafting machine or like device, two members pivoted with respect to each other, a cam fixed with respect to one of said members and eccentric with respect to the pivotal axis therebetween, said cam being generally elliptical in shape and having its minor axis substantially in the plane of the center of the cam and said pivotal axis, a cam follower supported by the other of said members for linear movement toward and

from said cam, and counterpoise spring means continuously urging said cam follower into engagement with said cam, said cam follower having an elongated transversely extending surface adapted to engage said cam whereby the counterpoising force of said spring is always exerted parallel to the direction of linear movement of said cam follower.

9. In a drafting machine or like device, a wheel member, a strut member pivotally supported with respect to said wheel member for rotation about an axis concentric therewith, a flexible band encircling said wheel member, a cam fixed with respect to one of said members and eccentric to said axis, said cam being generally elliptical in shape and having its minor axis substantially in the plane passing perpendicularly through the center of the cam and the axis of said one member, a cam follower supported by the other of said members for linear movement toward and from said cam, and counterpoise spring means carried by the other of said members continuously urging said cam follower into engagement with said cam, said cam follower having an elongated transversely extending surface adapted to engage said cam whereby the counterpoising force of said spring is always exerted parallel to the direction of linear movement of said cam follower.

10. In a drafting machine or like device, a wheel member, a strut member, means including a pivot fixed with respect to said wheel member for pivotally connecting said members for relative rotation about the center of said wheel member as an axis, a flexible band encircling said wheel member, a cam at one end of said pivot and eccentric thereto, said cam being generally elliptical in shape and having its minor axis substantially in the plane of the centers of the cam and the pivot, a cam follower movably supported by said strut member for linear movement toward and from said cam, said cam follower having a plane surface normal to the direction of the linear movement of the cam follower adapted to engage said cam, and counterpoise spring means carried by said strut continually urging said cam follower into engagement with said cam.
